[57] **CLAIM**

The ornamental design for a shoe sole bottom and side, as shown and described.

DESCRIPTION

FIG. 1 is an elevational view of one side of a shoe sole bottom and side showing my new design;

FIG. 2 is an elevational view of the other side of the shoe sole bottom and side;

FIG. 3 is an elevational view of the front of the shoe sole bottom and side;

FIG. 4 is an elevational view of the rear of the shoe sole bottom and side;

FIG. 5 is a cross sectional view taken along line 5—5 of FIG. 2;

FIG. 6 is a bottom plan view of the shoe sole bottom and side; and,

FIG. 7 is a cross sectional view taken along line 7—7 of FIG. 6.

The broken line showing of the upper in FIGS. 1-4 forms no part of the claimed design.

FIG. 1

FIG. 2

FIG. 5

FIG. 4

FIG. 3

FIG. 6

FIG. 7
